UNITED STATES PATENT OFFICE.

CARL OTTO HENRY MILLER, OF WILLIAMSPORT, PENNSYLVANIA.

RAIL-JOINT.

SPECIFICATION forming part of Letters Patent No. 715,110, dated December 2, 1902.

Application filed September 22, 1902. Serial No. 124,849. (No model.)

To all whom it may concern:

Be it known that I, CARL OTTO HENRY MILLER, residing at Williamsport, in the county of Lycoming and State of Pennsylvania, have 5 invented certain new and useful Improvements in Rail-Joints, of which the following is a specification.

My invention relates to railroad-rail joints, and has for its object to provide an improved 10 joint of that character such as will lessen, if not entirely obviate, all jarring of passengers caused by hammering of the car-wheels as they roll from rail to rail across the spaced ends thereof with joints as heretofore commonly formed.

The invention consists in novel arrangement of parts and special details of construction, which I will now proceed to describe in detail.

20 For a full understanding of my invention reference is had to the accompanying drawings, forming a part of this specification, and in which—

25 Figure 1 is a perspective view showing my improved joint with the ends of the rails in normal position; and Fig. 2 is a similar view with the ends of the two rails shown spaced apart, illustrating the peculiar construction involved.

30 In carrying out my invention I form a V-shaped recess A in the head of one rail at the end thereof and a similar or V-shaped tongue or projection B from the head of the next rail, substantially as shown in Fig. 2 of my drawings. The side walls of the recess A are provided with grooves C, and the side walls of 35 the tongue or projection B have ribs D, adapted to enter and in shape corresponding to the grooves C in the recess A. It will be noticed 40 that the recess A and the tongue B are formed leaving shoulders E, which abut when two ends of the rails come together.

With the ends of the rails joined as invented by me it is apparent that the tongue 45 B will provide a permanent bridge at the meeting ends of two rails and in addition a smooth and practically unbroken wheel-support at the rail-joints. Increased advantage resides in the use of the grooves C and 50 the ribs D, since when a joint is being formed they serve as guides, insuring proper alignment of the rails and when the joint is formed

lock the tongue extension B against vertical movement, and the latter resting in the recess A will hold the end of that rail down 55 upon the cross-ties. In fact, both rails are securely locked against either upward or downward movement.

In laying the rails the ends thereof should be spaced apart or placed close together, according to whether it be summer or winter at 60 that time, and thereby allow for the obvious expansion or contraction of the rail due to heat or cold effects well understood.

I would have it understood that my invention comprehends providing each rail with a recess A at one end and a tongue B at its other end also that one rail may have recesses, such as A, at both ends and the next with tongues or projections B at both of its 70 ends. In providing alternate rails, one with recesses at both ends and the other rail with tongues at both ends, obviously one or more sections of rail may be taken up and turned end for end to provide new wearing-surface. 75

My invention affords further advantage in rendering the use of less cross-ties for proper support to the rails and does not require splice-bars or other fastening means than the common spikes used for securing rails upon 80 the crossties.

Having thus fully described my invention, what I claim as new, and desire to secure by Letters Patent, is—

1. A rail-joint employing a V-shaped recess 85 in the end of one rail, and a like-shaped projection from the end of the adjoining rail, independent means within the said recess and forming a part of the said projection whereby either rail is prevented from upward 90 or downward movement, substantially as described.

2. A rail-joint employing a V-shaped recess in the head of one rail and a like-shaped projection from the head of the adjoining rail, 95 the said recess and projection being formed leaving shoulders on both sides thereof and adapted to prevent either rail from upward or downward movement and at the same time provide a smooth unbroken upper surface 100 connection between the ends of the two rails, substantially as described.

3. The combination in a rail-joint of a V-shaped recess in the head of one rail, a like-

shaped projection from the head of the adjoining rail, grooves in the side walls of the said recess, and ribs on the side walls of the said projection adapted to enter the said 5 grooves and together provide guides adapted to insure proper alinement and a smooth upper surface to the rails, substantially as described.

4. In combination, a recess in the rail-head

at opposite ends thereof, a like-shaped projection at opposite ends of the adjoining rail, 10 grooves in the side walls of each recess, and ribs on the side walls of each projection, substantially as described.

CARL OTTO HENRY MILLER.
